UNITED STATES PATENT OFFICE.

LEVIN FAUST AND WILLARD A. BROLIN, OF ROCKFORD, ILLINOIS.

SECTIONAL BOOKCASE.

No. 837,293.

Specification of Letters Patent.

Patented Dec. 4, 1906.

Application filed April 20, 1906. Serial No. 312,776.

To all whom it may concern:

Be it known that we, LEVIN FAUST and WILLARD A. BROLIN, citizens of the United States of America, residing at Rockford, in the county of Winnebago and State of Illinois, have invented certain new and useful Improvements in Sectional Bookcases, of which the following is a specification.

Our invention relates specifically to mechanism for equalizing the travel of the opposite ends of bookcase doors or closures and bureau and other sliding drawers and similar slidable parts of furniture; and it consists, essentially, of a case or similar structure having two single guideways therein extending transversely thereof and substantially parallel to each other from the front to the rear portion of the same, one of said guideways curving thence inward and extending along lengthwise of the case-section and thence backward into confluence with the remaining guideway, the confluent guideways curving thence backward and inward and extending along lengthwise of the case-section, a closure for the opening in the structure, and metallic tapes connecting with the end portions of such closure and extending therefrom lengthwise through the two single guideways and into the confluent guideways, said tapes being united at their rear end portions.

Referring to the accompanying drawings, which form a part of this specification, Figure 1 is a top plan view of a bookcase provided with our improvement having parts thereof horizontally sectioned away to show the interior construction, arrangement, and operation of the movable parts of the same. Fig. 2 is a like view of the same with parts thereof in different positions from those shown in Fig. 1, which last-mentioned figure shows the closure of the bookcase wide open and slid inward to its backward limit of travel, while Fig. 2 shows the closure slid outward to its forward limit of travel ready to be swung vertically downward to a closed position. Fig. 3 is a transverse section at the dotted line 3 3 in Fig. 1 of the bookcase closed. Fig. 4 is a section at the dotted line 4 4 in Fig. 1 of the upper portion of a complete case minus its closure. Fig. 5 is an enlarged sectional detail through the dotted line 5 5 in Fig. 3 of the left-hand half of the case. Fig. 6 is a section at the dotted line 6 6 in Fig. 2 of parts there shown.

Like letters of reference indicate corresponding parts throughout the several views.

A is a rectangular section of a sectional bookcase of the usual or any desired construction having two single guideways A' A² 60 therein extending transversely thereof and substantially parallel to each other from the front to the rear portion of the same, the guideways A' curving thence inward and extending along lengthwise of the case-section and thence backward to a³, Fig. 5, into confluence with the guideway A², the confluent guideways A³ curving thence backward and inward and extending along lengthwise of the case-section. 70

B is a partition arranged below and parallel to the top of the case-section A a sufficient distance therefrom to form a recess therein for the admission of the closure thereof when it is swung to a horizontal position, as indicated in Fig. 3, preparatory to being slid into the case-section. 75

C is a closure for the opening in the front of the case-section A and is horizontally slid- 80 able in the recess C', Fig. 3, in the top of the same.

DD' are metallic tapes (formed, preferably, of thin strips of flexible steel) pivotally connected, by means of pintles D² D³, with the end portions of the closure C and extending therefrom lengthwise through the single guideways A' A² and thence into the confluent guideways A³, where they are joined together by their inner ends at a, Fig. 5, such pintles D² D³ projecting into the grooves 90 D⁴ D⁵ in the case-section A and serving as 85 slideable bearings for the closure C.

If the closure C be swung from its vertical position, Fig. 3, to a horizontal position (indicated by the dotted lines a') and be slid 95 thence backward to its inner limit of travel, as in Fig. 1, the tapes D D' will have traveled inward with the closure a corresponding distance, their united ends a meanwhile having slid toward the right hand—from the 100 position they occupy in Fig. 2 to the position they are shown as occupying in Fig. 1—also a corresponding distance in the open end of the confluent guideways A³, Fig. 2. The tapes D D' being formed of inelastic 105 and longitudinally-unyielding material will obviously serve to positively and accurately equalize the slidable travel of a bookcase closure, a bureau or other drawer, or any similar sliding part in furniture or elsewhere. 110

Having fully described our invention, what we claim as new, and desire to secure by Letters Patent, is—

1. In combination, a case-section or analogous structure having two guideways therein extending transversely thereof and substantially parallel to each other, from the front to the rear portion of the same, one of said guideways curving thence inward and extending along lengthwise of the section, and thence backward into confluence with the remaining guideway, the confluent guideways curving thence backward and inward and extending along lengthwise of the section, a closure for the opening in the structure and metallic tapes connecting with the end portions of said closure and extending therefrom lengthwise through the two guideways and into the confluent guideways, said tapes being united at their rear end portions, substantially as described and for the purpose specified.
2. In combination, a case-section or analogous structure having two guideways A' A^2 therein extending transversely thereof and

substantially parallel to each other, from the front to the rear portion of the same, one of said guideways A' curving thence inward and extending along lengthwise of the section and thence backward into confluence with the remaining guideway A^2 , the confluent guideways A^3 curving thence backward and inward and extending along lengthwise of the section, a closure C for the opening in the structure and metallic tapes D connecting with the end portions of said closure and extending therefrom lengthwise through the guideways A' A^2 and into the confluent guideways A^3 , said tapes being united at their rear end portions, substantially as described and for the purpose specified.

In testimony whereof we have signed our names to this specification in the presence of two subscribing witnesses.

LEVIN FAUST.
WILLARD A. BROLIN.
